UNITED STATES PATENT OFFICE

155,270

DESIGN FOR A MICROPHONE

Louis R. Burroughs, South Bend, Ind., and Melvin H. Boldt, Glenview, Ill., assignors to Wilcox-Gay Corporation, Charlotte, Mich., a corporation of Michigan

Application August 21, 1947, Serial No. 140,970

Term of patent 14 years

(Cl. D26—14)

To all whom it may concern:

Be it known that we, Louis R. Burroughs and Melvin H. Boldt, citizens of the United States, residing respectively at South Bend, county of St. Joseph, State of Indiana, and Glenview, county of Cook, and State of Illinois, have invented a new, original, and ornamental Design for a Microphone, of which the following is a specification, reference being had to the accompanying drawing, forming a part thereof.

We claim:
The ornamental design for a microphone, as shown.

LOUIS R. BURROUGHS.
MELVIN H. BOLDT.
